UNITED STATES PATENT OFFICE

2,049,527

COIN SLOT MECHANISM

Hans C. Stockel, Chicago, Ill.

Application April 18, 1932, Serial No. 605,846

13 Claims.

(Cl. 235—32)

More particularly the invention relates to a device for receiving tokens of a plurality of predetermined sizes which may be inserted therein and which will not receive tokens of intermediate sizes.

An object of the invention is to provide such a coin slot mechanism of new and improved construction arranged to receive large and small tokens and to reject tokens of an intermediate 10 size.

Another object is to provide such a mechanism embodying separate registering devices for each size of token.

Another object is to provide a new and improved coin slot mechanism arranged to receive and to register coins of different sizes and in which the coins pass into the mechanism in substantially a straight line when inserted.

Another object is to provide such a mechanism 20 in which coins of a selected size may be inserted and registered and which embodies means for ejecting coins of another size.

Another object of the invention is to provide a coin slot mechanism in which coins may be 25 inserted in an open-ended slot and embodying means permitting the passage of small and large coins and to prevent the insertion of coins of an intermediate size, the passage of a coin being accomplished when the person inserting the coin 30 continues to press on the coin after it has been inserted in the slot so as to move the coin farther into the slot and at the same time move an adjacent member with the coin.

In its preferred form the invention is adapted 35 for the reception and registration of nickels and dimes, the coins being inserted by a single movement in substantially a straight line, and embodies means effective to prevent the insertion 40 of pennies.

Further objects and advantages of the invention will be understood from the following detailed description taken in connection with the accompanying drawings, in which:

45 Fig. 1 is an inclined plan view of a preferred form of the invention, along the arrow 1 of Fig. 2.

Fig. 2 is a section approximately along the line 2—2 of Fig. 1.

Fig. 3 is a section along the line 3—3 of Fig. 2.

50 Fig. 4 is a fragmentary section approximately along the line 4—4 of Fig. 1, showing the parts in their normal positions prior to the insertion of a coin.

55 Fig. 5 is a similar view showing the parts in

another position during the insertion of a large coin or nickel.

Fig. 6 is a section approximately along the line 6—6 of Fig. 1, showing the parts of the slot mechanism and the registering means for the smaller coins or dimes prior to the insertion of such a coin.

Fig. 7 is a similar view of the parts during the insertion of the smaller coin.

Fig. 8 is a view similar to Figs. 4 and 5, but 10 with the slot mechanism parts in their locked position during the insertion of an intermediate sized coin.

Fig. 9 is a section approximately along the line 9—9 of Fig. 8.

Fig. 10 is a section approximately along the line 10—10 of Fig. 8.

Fig. 11 is a fragmentary section similar to Fig. 9 showing the ejecting means in the out-of-the-way position it assumes upon insertion of a coin 20 of proper size.

While my invention is susceptible of embodiment in many different forms, I have shown in the drawings and shall herein describe in detail one such embodiment, with the understanding 25 that the present disclosure is to be considered as an exemplification of the principles of the invention and is not intended to limit the invention to the embodiment illustrated. The scope of the invention will be pointed out in the appended 30 claims.

In the form chosen for purposes of disclosure the invention embodies a pair of registering mechanisms, one for small and one for large coins, together with a movably mounted coin chute normally held in a raised position, means normally holding the chute in its raised position operable when a large coin is inserted to release the chute for downward movement, means operable during downward movement after a large coin has been 40 inserted to actuate the large coin register and pass the coin through the chute without operating the small coin register, said holding means also being released by a small coin when inserted in the chute to release the chute, means operable by 45 movement of the chute when a small coin has been inserted to operate the small coin register without operating the large coin register, said holding means being effective when an incorrectly sized coin is inserted in the chute to prevent 50 downward movement of the chute, and means for ejecting such coins from the chute.

As illustrated in the drawings, the invention comprises generally a somewhat rectangular casing 12 having an inclined cover 13, this casing be- 55

ing mounted on a supporting member or frame 13^a containing a cash box 12^a. The cover 13 is provided with an aperture 14 (Figs. 4 and 10) in which a split mounting member 15 is positioned and also has apertures 17 and 18 through which the number dials 19 and 20 of registering mechanisms 21 and 22 are visible. The registering mechanisms, as hereinafter more fully described, are arranged to count the number of small and large coins respectively which are inserted through the coin slot mechanism. The split mounting member 15 is secured to the cover 13 by a circular plate 25 mounted against the cover. This plate is provided with a recess 26 in its upper surface and a slot 27 extending downwardly from the bottom of the recess. In the slot 27 there is mounted a reciprocatory member 28 having a coin slot 29 therein. This member 28 is normally urged to its upper or extended position by means of coiled springs 30 secured intermediate arms 31 on the member and anchoring devices 32 on the casing, and is arranged normally to be held in its upper or extended position wherein it projects into the recess 26. A latch device 33, illustrated most clearly in Fig. 6, is pivotally mounted at 34 on the member 28 and has a laterally projecting portion 35 arranged to engage in a notch 36 in the mounting member 15 so as to hold the member 28 in its extended position. A spring 37 is arranged to hold said device in its latched position as shown in Fig. 6. Thus the right-hand end of the coin slot 29 (Fig. 6) is formed by the lever 33. Preferably a guard 37^a is provided on the member 28 to overlie the upper end of the latch device 33 so as to prevent operation of the latch device by means other than tokens.

The other end of the coin slot 29 is herein disclosed as being formed by an arm 40 pivotally mounted at its upper end on a pin 41 in the reciprocatory member 28. At its lower end this arm carries a transversely extending pin 42 (Figs. 3 to 8, and 10) which projects through an arcuate slot 43 in the member 28 and arcuate slots 44 in the mounting member 15. This arm is normally held in the position illustrated in Figs. 4 and 6 by a coiled spring 38 which is anchored at one end by a pin 39 to an intermediate portion of the arm 40 and at its other end to the mounting member 15. The member 28 is provided with an arcuate slot 39^a through which the pin 39 extends, the mounting member 15 being recessed at 45 to provide clearance for the pin 39 during the reciprocatory movement of the member 28.

In the preferred form of the invention the lever 40 is arranged to control the registering of the coins of proper size and to prevent the insertion of coins of incorrect size. As illustrated in the drawings, additional slots 46 and 47 are provided in the mounting member, which slots connect at their upper ends with the arcuate slot 44 at laterally spaced points so as to provide a locking abutment 48 therebetween. Thus if a large sized coin 50 (Fig. 4) is inserted in the slot 29 the coin will engage the lever 40 and swing it about its pivot 41 until the pin 42 has moved in the slots 43 and 44 to a position wherein it coincides with the adjacent end of the slot 47. During this movement the coin 50 has also engaged the upper end of the latch 33 so as to release the latch. The parts are preferably so arranged that when the upper edge of the coin becomes flush with the upper edge of the member 28 the latch 33 is released and the pin 42 is in a position above the open end of the slot 47. Thereupon

by continuing the inserting pressure on the coin and depressing the member 28 with the coin, the pin 42 enters the slot 47 as illustrated in Fig. 5, and as the pin reaches the bottom of the slot the lever 40 has been swung to such an extent 5 as to pass the coin 50 through the member 28 and into the cash box.

Means is provided to actuate the large coin register 21 during the passing of a large coin into the cash box. As illustrated herein a register 21 is provided with an operating arm 55 having a pin and slot connection 56 with a lever 57 pivotally mounted on the mounting member 15 at 53. The lever 57 is normally held in the position illustrated in Fig. 5 by means of a suitable coiled 15 spring 59 and is provided with a portion of the abutment 66 arranged to be engaged by the pin 42 when the pin moves in the slot 47 so that as the pin moves from the position illustrated in Fig. 5 to the left-hand end of the slot the lever 20 57 is pivoted and the register 21 actuated.

In Figs. 6 and 7 the relation of the various parts is illustrated during the passage of a small coin 65 through the slot 29. The slot 46 in the depending portion 15 of the mounting member is 25 so positioned that when a small coin has been inserted in the slot 29 it swings the arm 49 to a position wherein the pin 42 coincides with the open end of the slot 46 at the same time the latch 33 is released. After the small coin 65 has 30 been inserted until its upper edge is flush with the upper edge of the member 28, the member 28 may be depressed, the pin 42 then passing into the slots 46 as illustrated in Fig. 7. As the arm 40 is swung away from the latch 33 the coin 65 35 passes through the member 28 and into the cash box. It is to be noted from Fig. 4 that the portion 60 of the actuating lever 57 for the large coin register does not extend across the slot 46 and therefore is not actuated by the pin 42 when 40 a small coin is inserted.

The means for actuating the small coin register during the insertion of a small coin 65 is herein illustrated as comprising (Figs. 6 and 7) a segmental lever 66 pivotally mounted on the 45 mounting member at 67 and having a pin and slot connection 68 with an actuating arm 69 on the small coin register 22. The lever 66 is provided with a projecting portion or abutment 70 which extends across the slot 46 and is engageable by the pin 42 (Fig. 7) when said pin moves into the slot 46. During the downward movement of the member 28 the lever 66 is therefore actuated and in turn operates the register 22. The lever 66 is normally held in the position illustrated in Fig. 6 by means of a coiled spring 71 and is provided with a cut-away portion at 72 which coincides with the slot 47 so that, when a large coin is inserted and the pin 42 moves into the slot 47, said pin does not engage the lever 66. 60

It is believed readily apparent that if coins of sizes differing from those illustrated as 50 and 65 are inserted in the slot 29, the pin 42 will not be moved into register with the slots 46 or 47 and that therefore the member 28 cannot be depressed. For example, with the pin 42 in the position shown in Fig. 4 any effort to depress the member 28 would be prevented by engagement of the pin 42 with the lower portion of the slots 44 in the portion 15 of the mounting member. This is true whether the pin 42 engages with the slots 44 to the right of the slot 46, between the slots 46 and 47 at 48, or beyond and to the left of the slot 47 (Fig. 4). Thus intermediate sized coins are prevented from passing 75

through the coin slot by the land or abutment 48 and smaller or larger coins are also kept out of the cash box.

Means is preferably provided for ejecting coins of incorrect size when an attempt is made to insert them. This means is herein illustrated as comprising an ejecting member 75 which is illustrated most clearly in Fig. 9, this member being pivotally mounted at 76 on the mounting member 15 and in a transversely extending slot 77 in said member. The ejecting device is illustrated in the form of a short arm normally extending across the coin slot 29, being held in said position by means of a coiled spring 78 connected at one end to the member 75 and anchored at its other end on the mounting member portion 15. Thus if an intermediate sized coin is inserted with the result that it is impossible to depress the reciprocatory member 28, upon releasing the coin it is ejected by the member 75. However, if a proper sized coin is inserted the member 75 is pivoted in a clockwise direction (Fig. 9) and as the member 28 is depressed the ejecting member is pivoted to an out-of-the-way position so as to permit the coin to pass through the slot 29 as illustrated in Fig. 11.

If desired gongs 80 and 81 may be provided, the gong 80 being arranged to be struck by a member 82 when the large coin register 21 is actuated and the gong 81 being arranged to be struck by a member 83 when the small coin register 22 is actuated.

The operation of the invention is extremely simple in that when a person inserts a coin and presses it into the coin slot, it is merely necessary to continue the pressure against the coin and the adjacent member 28 to force the coin through the slot and to register it. Enabling coins to be inserted by movement in a single or straight line direction is of particular advantage, particularly when embodied in a mechanism arranged to register coins of several sizes, and to eject coins of incorrect sizes.

In the preferred form of the invention the member 28 is normally held in its extended position not only by the springs 30, but by the arm 40 and pin 42, and also by the latch device 33. It is readily apparent that the member can only be depressed when the pin 42 has been moved into alignment either with the slot 46 or the slot 47. The latch device 33, together with its guard 37^a, is provided so as to prevent persons from actuating the arm 40 by means of an improper instrument. The guard 37^a extends into the coin slot slightly beyond the edge of the latch device so that the latch device is not actuated until the upper edge of the coin is flush with the surface of the member 28. This arrangement would make it difficult for a person to operate the arm 40 by means of an improper instrument, since in order to depress the member 28 it would be necessary at the same time to actuate the latch device.

The slots 46 and 47 are formed so that if the pin 42 has entered one of said slots and the member 28 is depressed, the pin 42 is moved somewhat transversely of the direction of movement of the member 28, thus swinging the arm 40 in a clockwise direction and permitting the coin to pass between the latch device 33 and the arm 40 and into the cash box.

I claim as my invention:

1. A device of the character described having, in combination, small and large coin registers, a movably mounted member having a coin slot

therein, means normally holding said member in an extended position, movably mounted means on said member movable by small and large coins inserted in said slot to first and second positions corresponding to the sizes of the coins, means operable by movement of said member when a small coin has been inserted in said slot to actuate said small coin register without actuating the large coin register, means operable by movement of said member when a large coin has been inserted in said slot to operate said large coin register without operating the small coin register, means for preventing operation of either of the registers by coins of other sizes, and means for ejecting coins of such other sizes. 15

2. A coin slot mechanism for receiving large and small coins of predetermined size comprising, in combination, a casing, a large coin register, a small coin register, a movably mounted coin chute having one end projecting from the casing 20 for receiving coins and the other end projecting into the casing for depositing coins therein, means normally holding said chute in its extended position, means operable by a coin inserted in said chute to release the chute, means operable by movement of said chute when a large coin is inserted therein to permit the coin to pass through the chute and to actuate the large coin register, means operable by movement of said chute when a small coin is inserted therein to 30 permit said coin to pass through the chute and to actuate said small coin register, means effective when a coin of incorrect size is inserted in the chute to prevent movement of the chute and thereby prevent passage of said coin there- 35 through, and means operable to eject said coin of incorrect size.

3. A coin slot mechanism comprising, in combination, a support having a passage therethrough, a member mounted in said passage for reciprocatory movement and having a coin slot associated therewith, a latch device normally holding said member at one end of its travel and having a portion projecting into said coin slot, an arm pivotally mounted on said member having a portion projecting into said coin slot, a laterally extending pin carried on the free end of said arm, said support and said member having parallel arcuate slots coinciding when the member is in said one position and in which said pin is adapted 45 to move when the arm is swung by coins inserted in the slot, a third slot in said support connected at one end with the arcuate slot in the support and positioned so that when a coin of proper size is inserted in the coin slot said pin will be moved 50 in said arcuate slots to the entrance of said third slot, said third slot being so shaped that during movement of said member and coin from the latched position said arm will be swung to permit the coin to pass through the coin slot. 60

4. A device of the character described comprising, in combination, a casing, small and large coin registers, a movably mounted member having a coin slot associated therewith, means normally holding said member in an extended position, movably mounted means on said member movable by small and large coins inserted in said slot to first and second positions corresponding to the sizes of the coins, means operable by movement of said member when a small coin has been 70 inserted in said slot to actuate said small coin register without actuating the large coin register, means operable by movement of said member when a large coin has been inserted in said slot to operate said large coin register without 75

operating the small coin register, and means for preventing operation of either of the registers by coins of another size.

5. A device of the character described comprising, a support, a member reciprocably mounted on said support and having a coin slot therethrough, means for holding said member in an extended position on the support, a part pivotally secured to said reciprocatory member, means 10 normally urging said part into the coin slot, means for releasing said holding means to permit said member to be depressed when coins of a preselected size are inserted, and means operating upon presentation of a coin of preselected 15 size for withdrawing said part from said slot when said member is depressed so as to permit the coin to pass through the slot.

6. A coin slot mechanism comprising, in combination, a casing, a small coin register, a large 20 coin register, a movably mounted coin chute, means operable by movement of said chute when a large coin is inserted to actuate the large coin register, means operable by movement of said chute when a small coin is inserted to actuate 25 said small coin register, and means effective when a coin of incorrect size is inserted to prevent movement of the chute and to eject said coin.

7. A coin slot mechanism comprising, in combination, a movably mounted coin chute depressible in the direction of coin movement when a proper coin is inserted therein, a plurality of 30 means for registering separately different sized coins of predetermined sizes inserted in said chute, means for preventing movement of the chute except when coins of said predetermined sizes are inserted and means operable by movement of said chute selectively to actuate the registering means corresponding to the coin inserted 35 in the chute.

40 8. A coin slot mechanism comprising, in combination, a coin chute depressible in the direction of coin movement, a plurality of means for registering separately large and small sized coins inserted in said chute, means operable during 45 movement of said chute selectively to actuate the registering means corresponding with the size of coin inserted in the chute and means for rejecting coins of an intermediate size.

9. A coin slot mechanism for receiving large 50 and small coins of predetermined size comprising, in combination, a casing, a large coin register, a small coin register, a movably mounted coin chute having one end projecting from the casing for receiving coins and the other end projecting 55 into the casing for depositing coins therein and movable in the direction of coin movement when inserted into the chute, means yieldably resisting movement of said chute in the direction of coin movement, means normally holding said chute in 60 its extended position, means operable by a coin of proper size inserted in said chute to release the chute, means operable by movement of said chute when a large coin is inserted therein to permit the

coin to pass through the chute and to actuate the large coin register, and means operable by movement of said chute when a small coin is inserted therein to permit said coin to pass through the chute and to actuate said small coin 5 register.

10. A coin slot mechanism comprising, in combination, a support, a member mounted on said support for reciprocatory movement and having a coin slot associated therewith, an arm pivotally 10 mounted on said member having a portion projecting into said coin slot and carrying means normally engaging said support to prevent movement of said member, which means is ineffective when a coin of proper size has been inserted in 15 said slot to prevent such movement, and means on said support effective to swing said arm out of said slot when said member is moved to permit the coin to pass through the coin slot.

11. A device of the character described comprising, in combination, a support, a member reciprocably mounted on said support and having a coin slot therethrough, a part pivotally secured to said reciprocatory member and normally extending partially into said coin slot, said 25 part carrying means normally engaging means on the support to prevent movement of said member, which means are disengageable by a coin of proper size inserted in said slot swinging said part, and means for withdrawing said part wholly 30 from said slot when said member is depressed so as to permit the coin to pass through the slot.

12. A coin slot mechanism comprising, in combination, a support, a member mounted on said support for reciprocatory movement and having a coin slot associated therewith, a latch device normally holding said member at one end of its travel and having a portion projecting into said coin slot from one edge thereof adjacent its entrance, an arm pivotally mounted on said 40 member and having a portion projecting into said coin slot from the other edge thereof, and a guard device overhanging the outer end of said latch device and projecting into the coin slot beyond the adjacent portion of the latch device. 45

13. A coin slot mechanism having, in combination, a support, a member mounted on said support for reciprocatory movement and having a coin slot associated therewith, a latch device normally holding said member at one end of its 50 travel and having a portion projecting into said coin slot from one side thereof, a part movably mounted on said member and having a portion projecting into said coin slot from the opposite side operable by a coin of proper size to release said support to hold said member at the same end of its travel, said latch device and part being both operable by a coin of proper size to release said member and means operable during movement of said member to withdraw said part and thereby 55 permit the coin to move through the coin slot. 60

HANS C. STOCKEL.
